UNITED STATES PATENT OFFICE.

RUDOLF L. GRAEFE, OF CHICAGO, ILLINOIS.

DESIGN FOR AN ADVERTISING-EASEL.

47,784.

Specification for Design.

Patented Sept. 7, 1915.

Application filed April 23, 1915. Serial No. 23,534. Term of patent 3½ years.

To all whom it may concern:

Be it known that I, RUDOLF L. GRAEFE, residing at Chicago, in the county of Cook and State of Illinois, have invented a new, original, and ornamental Design for Advertising-Easels, of which the following is a specification, reference being had to the accompanying drawing, forming a part thereof.

I claim:

The ornamental design for an advertising easel as shown.

In witness whereof, I have hereunto subscribed my name.

RUDOLF L. GRAEFE.
